UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed December 7, 1923. Serial No. 679,214.

My invention relates to mining apparatus.

An object of my invention is to provide an improved mining apparatus. Another object of my invention is to provide an improved mining machine especially adapted to cut kerfs in a vertically disposed plane. Still another object of my invention is to provide an improved mining mechanism including a machine of the flexibly fed type, 10 herein of standard construction, provided with improved supporting or skid means, adapted to cut kerfs in a vertical plane and especially adapted to cut downwardly disposed kerfs in the coal strata in accordance 15 with the "strip or open pit" system of mining. It will herein be noted that under some conditions encountered in coal mining it is desirable and even necessary to work from the top of the coal strata instead of 20 working laterally into a face as is the usual system. This is peculiarly advantageous when the "strip or open pit" system is used, the coal strata being exposed near the surface, for instance, by mechanical shovels. 25 In accordance with this method of mining the coal strata is cut in a series of narrow strips, blocks, or other desired sections. The coal is then drilled with "shot" holes and the coal "shot from the solid." A still further object of my invention is to provide improved mechanism for use in this system of mining. These and other objects and advantages will hereinafter more fully appear.

In the accompanying drawings I have 35 shown for purposes of illustration one form which my invention may assume in practice.

In these drawings,—

Fig. 1 is a side elevation view of a mining machine constructed in accordance with one 40 illustrative embodiment of my invention.

Fig. 2 is an end elevation view of Fig. 1, partially in section.

In the illustrative form of my invention I have shown a mining machine, generally 45 designated 1, herein of standard form, provided with a longitudinally extending frame 2, which is comprised of three sections, i. e. a motor section 3, a feed section 4, and a cutter mechanism carrying section 5, the 50 feed and cutting mechanism carrying sections 4 and 5 herein being disposed at opposite ends of and rigidly connected to, the motor section 3 in the usual manner. The frame 2 of the mining machine is disposed 55 on its edge or side 6, with its bottom plate

6' disposed in a vertical plane, on a skid, generally designated 7, of improved form to be hereinafter described, which is slideable on the surface of the coal strata. For the purpose of moving the machine there is 60 provided a flexible feeding member 8, herein in the form of a chain, which is guided by a plurality of guide sheaves or rolls 9 rotatable on horizontal axes on the frame section 4 and suitably drawn in by a feed sprocket 10 rotatable at a predetermined cutting speed and at a higher speed, said higher speed being used to haul the machine about the mine in a usual manner. The sprocket 10 is 65 rotatable on a horizontal axis parallel with the axes of the sheaves 9 and is likewise carried by the feed frame section 4, and is driven by the motor through suitable connections (not shown), which may be of any 70 approved form. It will be observed that the frame section 5 carries a cutter bar 11 pivoted on a transverse horizontal axis 12 parallel with the axis of the feed sprocket 10 and which cutter bar is adapted to be swung 75 downwardly into the coal strata, herein by extending the feed chain 8 beneath the machine and connecting the same to a pivoted two-part hook 13, indicated by dotted lines in Fig. 1, which is in turn adapted to be 80 connected to a laterally projecting abutment 14 formed integral with the cutter bar. As the bar is swung downwardly it cuts a narrow 85 vertical kerf until it reaches a position substantially perpendicular to the plane of the bottom of the skid 7 and is then rigidly locked in position by means of a pin 15 registering with one of a plurality of openings 90 16 formed in a circular flange 17 which is adapted to guide the cutter bar during its swinging movement. It will herein be noted 95 that instead of using the feed chain to sump in the cutter bar the bar may swing into the coal by means of gravity alone. It will also be noted that the cutter bar may be removed from the kerf by suitably connecting the feed chain 8 in its opposite relation with respect to the machine frame and cutter bar. Herein it will be further noted that the cutter bar 11 is provided with an endless cutter bit carrying cutter chain 18 which is adapted 100 to be circulated around the cutter bar by the motor 3 through connections (not shown) in a well known manner.

As previously stated, the mining machine is of standard construction turned on its 110

- side and mounted on a skid of improved form 7. In my improved construction it will be observed that a mine surface engaging shoe or skid 19 is provided preferably having upturned curved front and rear ends 20 and slightly upturned curved sides 21 to permit a free sliding movement of the bottom plate on the surface of the coal strata or relative to a transport truck (not shown).
- 10 As shown, a pair of angle members 22 is disposed longitudinally beneath the side of the mining machine 1 at the desired distance apart and rigidly connected to the latter by means of suitable screws 23, while operatively connected between the depending portion of the right hand angle 22, herein by rivets 24 (see Fig. 2) is an intermediate support herein in the form of another angle iron 25 likewise longitudinally disposed, while the left hand angle member 22 is rigidly connected by means of rivets 26 to a vertically disposed plate 27 suitably secured to the bottom plate 6' of the mining machine and to an intermediate supporting angle member 28 disposed parallel with the member 25. Herein it will be noted that the angle members 25 and 28 are rigidly secured to the bottom plate 19, preferably by rivets 26'. It will further be noted that a plurality of brace members 29, herein three, are disposed between the vertically disposed bottom plate 6' of the machine and the skid bottom plate 19 being rigidly connected thereto by means of screws and rivets 30 and 31 respectively.
- 30 35 It will be observed that the bottom plate 19 and the angle members 22, 25 and 28 form an opening 32 extending longitudinally beneath the machine through which the feed chain 8 passes during the bar swinging operation.
- 40 As a result of my improved construction, it will be evident that it is possible to provide a support for a mining machine constructed to work in accordance with the 45 "strip or open pit" system of mining and which is exceedingly simple and rugged and manufactured at a minimum of expense. These and other advantages will be clearly apparent to those skilled in the art.
- 50 55 While I have in this application specifically described one form which my invention may assume in practice, it will be understood that this form of the same is shown for purposes of illustration and that the invention may be modified and embodied in various other forms without departing from its spirit or the scope of the appended claims.
- 60 What I claim as new and desire to secure by Letters Patent is:
- 65 1. In a mining apparatus, a mining machine having an elongated cutter bar disposed in and mounted for movement in a vertical plane, said cutter bar being provided with cutting elements arranged to cut a kerf to admit said bar, and feeding means there-
- for, and supporting means for said machine comprising a skid having machine supporting portions providing an opening between the skid and said machine through which a portion of said feeding means is adapted to be extended at will.
2. In a mining apparatus, a mining machine normally cutting on its own bottom and provided with an elongated cutter bar having cutting elements arranged to cut a kerf to admit said bar, and means for operating said machine with its bottom in a vertical plane comprising a bottom engaging skid upon which the side of the machine is immovably secured.
3. In a mining apparatus, a mining machine normally cutting on its own bottom and provided with an elongated cutter bar having cutting elements arranged to cut a kerf to admit said bar, and means for operating said machine with its bottom in a vertical plane comprising an intermediate support on which the side of said machine is immovably secured and a bottom plate slideable on the mine bottom.
4. In a mining apparatus, a mining machine normally cutting on its own bottom and means for operating said machine with its bottom in a vertical plane comprising a bottom plate forming a sliding bottom engaging support, an intermediate support attached thereto, and a plurality of longitudinally spaced bracing members disposed between said machine and said bottom plate.
5. In a mining apparatus, a mining machine having a pivoted cutter bar movable in a vertical plane, means for swinging said bar including a flexible element, and supporting means for said machine comprising a skid having an opening through which said flexible element passes.
6. In a mining apparatus, a mining machine normally slideable on its own bottom operating as an under cutter, said machine having an elongated cutter bar provided with cutting elements arranged to cut a kerf to admit said bar, and means for supporting said machine with its bottom in a vertical plane for operation as a vertical cutter comprising a horizontal widely extended bottom engaging skid on which the side of said machine is immovably secured.
7. In a mining apparatus, a mining machine normally cutting on its own bottom and having a pivoted cutter bar, means for swinging said bar including a flexible element, and supporting means for said machine comprising a skid to which the latter is rigidly secured having an opening through which said flexible element passes.
8. In a mining apparatus, a mining machine normally cutting on its own bottom and having a pivoted cutter bar, and means for operating said machine on its side with its bottom in an elevated position compris-

ing a bottom plate forming a bottom engaging sliding support, an intermediate support attached thereto, and a plurality of longitudinally spaced bracing members disposed between said machine and said bottom plate.

9. In a mining apparatus, a mining machine normally cutting on its own bottom, and means for operating said machine on its side with its bottom in a vertical plane comprising a bottom plate forming a bottom engaging sliding support, an intermediate support attached thereto and to the side of said machine, a longitudinally extending bracing member engaging said bottom plate and said support, and a plurality of longitudinally spaced bracing members secured to said machine and to said bottom plate.

10. In a mining apparatus, a mining machine normally cutting on its own bottom, said machine being provided with an elongated cutter bar having cutting elements arranged to cut a kerf to admit said bar, means for operating said machine with its bottom and cutter bar in a vertical plane comprising a bottom engaging skid to which the side of the machine is rigidly secured, and means for feeding said machine including a flexible element, a feed operating member rotatable on a horizontal axis, and guiding means for said flexible member disposed adjacent said feed operating member.

11. In a mining apparatus, a mining machine normally cutting on its own bottom and having a pivoted cutter bar, means for feeding said machine and for swinging said bar including a flexible element, supporting means for said machine whereby the latter may be operated with its bottom in a vertical plane, said supporting means providing

an opening therethrough beneath said machine, and means whereby said flexible element may be selectively extended rearwardly through said opening and attached to said bar to swing the latter or forwardly to a fixed extraneous abutment to feed the machine longitudinally.

12. In a mining apparatus, a horizontal widely extended skid slideable on the mine bottom, a mining machine immovably secured in an elevated position on said skid and provided with an angularly adjustable elongated cutter bar mounted for swinging movement in a vertical plane extending longitudinally of said skid and between the lateral limits thereof, said cutter bar being provided with cutting elements arranged to cut a kerf to admit said bar, and means operated by the machine to feed the later over the mine bottom and to swing said bar.

13. In a mining apparatus, a horizontal widely extended skid slideable on the mine bottom, a mining machine immovably secured in an elevated position on said skid and provided with an angularly adjustable elongated cutter bar mounted for swinging movement in a vertical plane extending longitudinally of said skid and between the lateral limits thereof, said cutter bar being provided with cutting elements arranged to cut a kerf to admit said bar, and means operated by the machine including a flexible element selectively connectible to said bar to effect swinging movement thereof or to a fixed extraneous abutment to effect feeding movement of the machine over the mine bottom.

In testimony whereof I affix my signature.

MORRIS P. HOLMES.

CERTIFICATE OF CORRECTION.

Patent No. 1,654,218.

Granted December 27, 1927, to

MORRIS P. HOLMES.

It is hereby certified that error appears in the printed specification of the above numbered patent requiring correction as follows: Page 3, line 58, claim 12, for the word "later" read "latter"; and that the said Letters Patent should be read with this correction therein that the same may conform to the record of the case in the Patent Office.

Signed and sealed this 14th day of February, A. D. 1928.

Seal.

**M. J. Moore,
Acting Commissioner of Patents.**
